UNITED STATES PATENT OFFICE.

ROBERT W. SCOTT, OF SPOKANE, WASHINGTON.

SAW HANDLE.

1,420,291.

Specification of Letters Patent. Patented June 20, 1922.

Application filed August 24, 1921. Serial No. 495,049.

To all whom it may concern:

Be it known that I, ROBERT W. SCOTT, a subject of the King of Great Britain (first papers being taken out to become a citizen of the United States), residing at Spokane, in Spokane County, and State of Washington, have invented certain new and useful Improvements in Saw Handles, of which the following is a specification.

10 The invention has reference to saw handles and particularly to a detachable handle for a cross-cut saw.

The main purpose and object of the invention is to provide a quick-detachable saw 15 handle of particular advantage in felling trees; the handle being quickly removable from the saw to permit the rapid withdrawal of the blade from the cut to prevent the injury or pinching of the latter by the falling 20 trunk.

A further object is to provide novel means 25 for attaching the handle to the blade whereby the handle will be held with sufficient firmness to withstand all strains to which it is subjected in the use of the saw.

With the above and other objects in view, the invention consists, generally, in the details of construction, combination and arrangement of parts as are hereinafter more 30 fully described, reference being had to the accompanying drawings, wherein:

Figure 1 is a side elevation, showing the detachable handle as attached to the end of a saw.

35 Figure 2 is a longitudinal vertical section of the handle and saw-end.

Figure 3 is a vertical cross-section of the handle, as taken on line 3—3 of Figure 1, and

40 Figure 4 is a view of a modified form of handle, the construction being slightly altered.

In the construction illustrated, numeral 10 designates an end portion of the cross-cut saw such as used in a timber country and 11 the hole for the bolt 12 of the handle. This bolt is provided at one end with a springy hook-bearing portion 13 which bears against one flat side of the saw blade as shown, the 45 hook 14 thereof passing through the hole and bearing against the opposite side of the blade. The other end of the bolt has a threaded portion 15 over which the usual wooden handle 16 is inserted, the latter having a recess or pocket in which is housed the bolt-receiving adjusting nut 17. Encircling

the bolt between the end of the saw blade and the handle is a locking device for securing the handle firmly in place to withstand the pull and strain incident to the use of the 60 saw. This device includes a guard member 18 adapted to bear against the saw blade and grooved, as indicated at 19 to receive the end of the blade, the groove serving to keep the guard firm and rigid during use. 65 The guard is of greater length than the width of the saw so as to project beyond both sides thereof, providing hand-grip for the sawyer as hereinafter explained. Projecting centrally from the guard opposite the 70 grooved face thereof is a hollow barrel 21 adapted to engage barrel 22 of the other member of the locking device. This other member is provided with a handle socket 23 integral with barrel 22 and having grooves 75 in the outer face, crossing at right angles to each other to provide socket grooves for handle 16. By having the grooves crossing at right angles it will be seen that handle 16 may be positioned at right angle to the 80 saw blade, when desired, by merely transferring it from one groove to the other. Barrels 21 and 22 have complementary quarter-sections cut out, as shown at 24, to allow each barrel to have an interfitting 85 sliding engagement with the other, the quarter section of one barrel fitting into the cut-outs between the quarter sections of the other barrel as shown to advantage in Figures 2 and 3. Housed within the interfitting 90 barrels and coiled about the bolt 12 is an expansion spring 25 which serves to keep the barrel spread apart with a certain amount of clearance between the inner end of each quarter section and the terminal of the slot 95 in which it slides, thereby permitting the barrels to be drawn together sufficiently to release the handle when necessary. This spring also serves to keep guard 18 firmly 100 pressed against the saw blade and the socket head 23 snugly against the handle, the pressure exerted outwardly against the handle tending to draw the back or shoulder edge of the bolt hook 14 tight against the rear wall of the bolt-hole while at the same pressure 105 is exerted in the opposite direction against guard 18; the handle being thereby clamped securely to the blade and in no wise disturbed or loosened by any pull exerted on handle 16 during the usual or ordinary 110 operation of the saw. Mounted on the barrel-portions of the handle lock is a rubber

or leather sleeve 26 which serves as a guard for covering the slots or cut-outs and hiding the spring; the ends of the guard being spaced inwardly from both the guard and 5 socket members to allow for the contraction of the members when releasing the handle.

Figure 4 shows a slightly altered construction of the guard and handle socket in that the barrel of one member telescopes over 10 the barrel of the other member, a pin 27 being carried by the inside barrel to operate in a slot 28 of the outside barrel to prevent a turning movement of the handle with respect to the guard.

15 In connection with the use and operation of the invention, it may be mentioned by way of preface, that, in felling a tree; to prevent pinching of the blade it is necessary to rapidly remove the same from the cut at 20 the time the tree starts to fall. As soon as the heel or back edge of the blade has buried itself in the trunk to the extent of several inches or more, a wedge is driven into the cut to throw the tree slightly away and enlarge 25 the cut to allow for clearance. As the tree starts to fall this wedge is tightly driven into the wood and the only way to pull the saw out is to remove the handle from one end and pull the saw through. With the 30 present day devices or saw handles time is required to unloosen and detach the handle. With the detachable handle herein provided for, however, the detachment can be almost instantaneously effected. As the tree is about 35 to fall, one of the sawyers may grasp the projected ends or handle-grips 20 of the guard member and draw the latter in toward the handle 16, compressing spring 25 and releasing the guard from the edge of the 40 saw blade. Upon swinging the handle away

from the blade hook 14 of the bolt will detach itself and slip through bolt-hole 11, thus entirely releasing the handle and permitting the other sawyer to pull the blade through the cut. The same application reversed is used to again attach the handle to the saw. As some saw blades have the bolt-holes at different distances from the end, to make this handle meet those conditions bolt 12 may be turned in nut 16 until 45 the right adjustment is obtained; the threaded end of the bolt being movable in the closed base or socket 27 of the handle, thus leaving a smooth handle free from any obstruction.

Having thus described the invention what I claim is:

1. The combination with a shank having a hooked end to engage an opening in a saw blade, of a pair of telescopic barrels and 60 means for retaining said barrels in longitudinal alinement, said barrels encasing the shank and an expansion spring within the barrels, a guard on one barrel engaging the saw blade, and a socket member on the other 65 barrel engaging a saw handle.

2. The combination with a shank having means for attachment to a saw blade, of a pair of telescopic barrels having coating means for retaining said barrels in longitudinal alinement, an expansion spring within the barrels and surrounding the shank, a guard on one barrel to engage the saw blade, and a socket member on the other barrel having angular grooves for engagement with a saw handle whereby the handle may be adjusted angularly of the saw blade.

In testimony whereof I affix my signature.

ROBERT W. SCOTT.
